UNITED STATES PATENT OFFICE

162,702

ATTACHMENT FOR GARMENT HANGER

Samuel L. Yett, Barre, Vt.

Application June 7, 1949, Serial No. 3,100

Term of patent 14 years

(Cl. D33—8)

To all whom it may concern:

Be it known that I, Samuel L. Yett, a citizen of the United States, residing at Barre, State of Vermont, have invented a new, original, and ornamental Design for Attachment for Garment Hanger, of which the following is a specification, reference being had to the accompanying drawing, forming a part hereof.

Referring to the drawing:

Fig. 1 is a front view of an attachment for garment hanger, showing my new design;

Fig. 2 is a side view of the attachment; and
Fig. 3 is a view on line 3—3 of Fig. 2.

I claim:

The ornamental design for an attachment for garment hanger, as shown.

SAMUEL L. YETT.
